UNITED STATES PATENT OFFICE.

WALTER J. BEATTIE, OF COHOES, NEW YORK, ASSIGNOR TO THE BEATTIE MANUFACTURING CO., OF COHOES, NEW YORK, A CORPORATION OF NEW YORK.

FOLDING-MACHINE.

1,341,409.

Specification of Letters Patent.

Patented May 25, 1920.

Application filed September 17, 1917. Serial No. 191,721.

To all whom it may concern:

Be it known that I, WALTER J. BEATTIE, a citizen of the United States, residing at Cohoes, county of Albany, and State of New York, have invented certain new and useful Improvements in Folding-Machines, of which the following is a specification.

Reference may be had to the accompanying drawings, and the reference characters 10 marked thereon, which form a part of this specification. Similar characters refer to similar parts in the several figures therein.

This invention relates to machines of the general type shown in U. S. Letters Patent 15 No. 1,167,329, granted to me January 4, 1916.

Certain objects of the invention are to simplify the construction and manner of operation; to economize in the use of the electric current in the operation of the machine; and to facilitate various adjustments 20 for adapting the machine for various uses.

Other objects will appear in connection with the following description.

Figure 1 of the drawings is a view in 25 front elevation of a folding-machine embodying my invention.

Fig. 2 is a view in elevation of the right-hand end of the machine as viewed in Fig. 1.

Fig. 3 is a view in rear elevation of the 30 same.

Fig. 4 is a top plan view of the machine with the templet removed, and the templet-carrying arm partly broken away.

Fig. 5 is a horizontal cross section of the 35 machine taken on the broken line 5—5 in Fig. 2.

Fig. 6 is a vertical longitudinal section of the machine taken on the broken line 6—6 in Fig. 4.

Fig. 7 is a horizontal cross section of the machine taken on the broken line 7—7 in Fig. 6.

Fig. 8 is a view in perspective of one of the 45 eccentric-straps for connecting an eccentric with a rear infolder.

Fig. 9 is a similar view of one of the eccentric-straps for connecting an eccentric with the front corner-infolder.

Fig. 10 is a vertical cross section taken on 50 the broken line 10—10 in Fig. 4, through the clamping connection between an eccentric-strap and an infolder.

Fig. 11 is a view in vertical cross section on a larger scale of that part of the infolder-

operating mechanism which is shown in vertical cross section in Fig. 1, including an eccentric and an eccentric-strap for operating one of the front corner-infolders; and a means whereby the intermediate front infolder is operated. 55

Fig. 12 is a plan view of the rotatory shaft having arms adapted to be connected with the toothed-racks whereby the infolders are operated.

Fig. 13 is a vertical cross-section taken on 65 the broken line 13—13 in Fig. 12, of the universal-joint-connection between one of said arms, and a link whereby said arm is connected by one of said racks.

Referring to the drawings wherein the invention is shown in preferred form, 1 is the frame of the machine, and 2 is a bed upon which the blanks are placed to be folded, which bed is vertically movable in an opening in the top, 3, of the frame. 70

A templet, 4, co-operates with the bed, 2, to hold the blank in position upon the bed, while the edges of the blank are inturned over the edges of the templet by means of infolders, 5, 5^a, and 5^b, movable inwardly 80 and outwardly over the bed. The templet is mounted upon an arm, 6, pivoted at 7 upon a bracket, 8, projecting from the frame of the machine whereby the templet is adapted to be moved toward and from the bed. The 85 templet may be of any known form.

For certain purposes I prefer to employ a templet which is automatically expandible and contractible by means of an eccentrically connected link 9, in substantially the 90 manner shown and described in U. S. Letters Patent No. 972,320, granted to me October 11, 1910, for folding-machines. As this feature of the templet, however, forms no part of the present invention, a detailed 95 description thereof will not be necessary.

I have shown two infolders, 5, arranged along the rear of the bed adapted to fold the rear edge and the neighboring corner portions or end portions of the blank. 100

Arranged along the front of the bed, I have shown two infolders, 5^a, adapted to fold the front corner portions of the blank, and an intermediate side infolder, 5^b, adapted to fold the remainder of the front edge 105 of the blank.

The two infolders, 5, are movably interconnected by means of a bar, 10, preferably

fixed to one of said infolders and slidably mounted in the companion infolder, each of said infolders being engaged by an eccentric, 11, operated by suitable mechanism whereby the infolders can be moved inwardly and outwardly, and toward and from each other in the manner set forth in U. S. Letters Patent No. 1,071,677, granted to John Maitland and myself August 26, 1913.

The front corner infolders, 5^a, are movably connected together by means of a bar, 10^a, preferably fixed in a slideway, 10^b, on one thereof, and longitudinally movable 15 in a similar slideway, 10^c, on the other thereof, each of said infolders, 5^a, being engaged by an eccentric, 11^a, operating in a manner similar to the eccentrics, 11. The intermediate front side infolder, 5^b, is movable inwardly and outwardly over the bed along a slide-bar, 110, the front end of which is pivotally mounted at 111 upon the top of the machine, leaving said slide-bar free for lateral self-adjustment as the infolder, 5^a, moves inwardly and outwardly.

Coil-springs, 112, tend to yieldingly hold the infolder, 5^b, in its outermost position and to restore it to said outermost position when released from other influences.

Inward movement is imparted to the infolder, 5^b, by means of a pair of levers, 113, pivoted respectively at 114, upon the top of the machine, the inner ends of said levers being connected by the respective links, 115, with said infolder, 5^b. The other ends of said levers, 113, are adapted to be engaged by respective cams, 116, in fixed relation to the respective eccentrics, 11^a, during the operation of the machine.

By properly locating or adjusting the position of the cams, 116, with relation to the respective eccentrics, 11^a, the movements of the infolder, 5^b, can be so timed and regulated with respect to the movements of the infolders, 5^a, as to secure most effective results in folding certain styles of blanks.

For example:—In the style of blank for which infolders shown in Fig. 4 are particularly adapted, the front or bottom edge of the blank is indented or concaved while the right-hand end of the blank is sharply upturned or hook-shaped.

In folding such a blank it is found difficult or impossible to provide for a sufficient inward movement of the infolder which folds the indented or incurved lower side edge of the blank by means of an infolding member which is integral with, or partakes of the same movement as, the infolding member which infolds the neighboring corner portions of the blank.

By the means shown, however, it will be seen that the degree of inward movement of the infolder, 5^b, is not dependent upon 65 the degree of inward movement of either of

the neighboring corner infolders, 5^a, because the degree of inward movement of the corner infolders, 5^a, is regulated by the throw of the respective eccentrics, 11^a, while the inward movement of the infolder, 5^b, is 70 regulated by the throw of the cams, 116, which can be made as prominent as may be desired.

The templet is normally held raised from the bed by means of a coil-spring, 12, connecting a rearward extension, 13, of the templet-arm, 6, with an eye, 14, on a stationary part of the machine.

The templet-arm is adapted to be drawn downward to force the templet against the bed, or the interposed blank, by means of a rod, 15, pivoted at 16, upon the templet-arm, and pivotally connected at 17, with the core, 18, of a solenoid, 19, whereby when an electric current is passed through the circuit of said solenoid, said rod, 15, will partake of the downward movement of the core, 18, and thus move the templet down upon the bed.

As a preferred means for operating the infolders, 5, I rotatively mount upon the frame of the machine in fixed relation to the respective eccentrics, 11, pinions, 20, adapted to be engaged by the toothed rack, 21, capable of longitudinal sliding movements 95 through a pair of slideways, 22, on the frame of the machine.

In like manner I rotatively mount upon the frame of the machine in fixed relation to the respective eccentrics, 11^a, pinions, 20^a, 100 adapted to be engaged by a toothed rack, 21^a, similar to the rack, 21, and similarly capable of longitudinal sliding movements through slideways on the frame of the machine.

The racks, 21 and 21^a, are preferably severally obliquely arranged with respect to a line extending from center to center of the two pinions engaged by the rack, whereby the rack engages the outer side of one 110 and the inner side of the other of said pair of pinions, by which arrangement similar converging, or similar diverging, movements can be imparted to both infolders operated by said rack, substantially as 115 shown and described in U. S. Letters Patent No. 1,167,329, granted to me January 4, 1916.

The respective racks, 21 and 21^a, and the pinions engaged thereby, are mounted on a 120 level below the plane of the top of the frame as shown in Figs. 1 and 3, while the eccentrics, 11 and 11^a, and the cams, 116, are mounted above the level of the top of the frame of the machine, as shown in said 125 figures.

The manner in which this is accomplished is particularly shown in Fig. 11, wherein a vertical shaft, 98, is shown rotatively mounted in a bearing in the top of the machine,

one of the pinions, 20^a, being fixed upon the lower end of said shaft below the top of the machine.

Adjacent to the upper side of the top of 5 the machine, the eccentric, 11^a, is adjustably secured upon said shaft, 98, by means of a set-screw, 99, inserted through a shaft-inclosing sleeve forming an upward extension of the eccentric; and immediately 10 above said eccentric the cam, 116, is adjustably secured upon said shaft, 98, by means of a set-screw, 100.

By means of the arrangement just described, the eccentrics and also the cams, 15 116, which determine the throw of the respective infolders are located above the top of the machine where they are readily accessible and can be easily adjusted to change the throw of the respective infolders from 20 time to time as may be found necessary.

The respective racks, 21 and 21^a, are connected by links, 23, with arms, 26, projecting in opposite directions from the upper end of a shaft, 27, rotatively mounted with- 25 in a hollow post, 28, forming part of the frame of the machine, and rigidly connected with the top of the machine by means of vertical members, 29, through the space between which members the arms, 26, project 30 and are free to play.

The arm, 26, at the front of the machine is extended to form a handle, 30, whereby the infolders can be operated by hand when desired.

35 The links, 23, are connected with the respective arms, 26, each by a universal joint, 101, which is adjustably mounted upon the respective arm, 26, by means of a screw-bolt, 102, adjustably movable along 40 a slot, 103, in said arm, 26, and secured in adjusted position by means of a nut, 103. By means of the adjustment thus provided, said universal joint, 101, can be mounted upon the respective arm, 26, at a greater or 45 less distance from the axis of the shaft, 27, to vary the throw of the respective racks, 21 and 21^a, and the length of movement of the eccentrics from time to time as may be desired or found necessary.

50 A pair of arms, 31 and 32, project in opposite directions from the lower end of the shaft, 27, the arm, 31, being connected by a link, 33, with the core, 34, of a solenoid, 35, so arranged that when an electric current is passed through the circuit of said solenoid, the movement of the core, 34, will be imparted through arm, 31, shaft, 27, and arms, 26, to the respective racks, 21 and 21^a, to operate the infolders in an inward direction.

A coil-spring, 97, which connects one of the arms, 26, with the frame of the machine tends to yieldingly hold the infolders withdrawn to their outermost position.

65 The movable bed, 2, is supported upon

a movable frame, 24, by means of four adjusting screws, 25, each supporting one corner of the bed, and whereby the bed can be leveled or adjusted when necessary.

The bed-supporting frame, 24, when not 70 in use for pressing the blanks, rests upon two posts, 36, projecting upward from a pair of arms, 37, which extend in opposite directions from the hollow post, 28, into which arms said posts, 36, are screwed 75 whereby they are capable of vertical adjustment when necessary. The posts, 36, thus support the frame, 24, near each end along the longitudinal middle of the frame.

By means of the supports and adjust- 80 ments thus provided, the bed can be very accurately positioned for proper coöperation with the templet and the infolders during the folding operation.

The adjusting screws, 25, directly engage 85 cross-bars, 38, upon which cross-bars the bed is supported by means of four lugs, 39, one at each corner of the bed. The bed itself may be of any desired form.

I have shown a hollow bed adapted to 90 receive an electrical heating element, which element is not shown.

The bed-supporting frame, 24, is provided with a central aperture, 40, adapted to receive the upper end, 41, of shaft, 27, which 95 is made of reduced diameter.

The shaft, 27, is mounted in the post, 28, with provision for vertical movement, and the bed-supporting frame is adapted to be engaged and raised by the body portion of 100 the shaft, 27, to accomplish the pressing of the folded blanks.

Sufficient lost motion is provided in connecting the links, 23, with the respective racks, 21, and arms, 26, and in connecting 105 the link, 33, with the arm, 31, and core, 34, of the solenoid, 35, to permit such vertical movement of the shaft, 27.

A rod, 42, extends from the lower end of the shaft, 27, to a pressing lever, 83, fulcrumed at one end at 84 upon the frame of the machine, the other end of said lever being engageable with the core, 43, of a solenoid, 44, and so arranged that when said solenoid is energized the lever, 83, is forced 110 upward, imparting upward movement to the rod, 42, shaft, 27, bed-supporting frame, 24, and bed, 2.

A coil-spring, 45, connects the pressing lever, 83, with the frame of the machine, 120 and serves to counterbalance a substantial part of the weight of the lever, 83 and the parts supported therefrom.

It will be seen that by energizing the solenoids, 19, 35 and 44, successively in the 125 order named, the templet will be forced down upon the bed, the infolders moved inwardly over the templet to inturn the edges of a blank held upon the bed by the templet, and the bed will be forced upward 130

to press the folded blanks so held between the bed and the infolders.

Electric current for energizing the solenoids is furnished by means of wires, 47 and 48, connected with a generator or other source of supply not shown.

The supply of electric current to the solenoid, 19, is controlled by an electric switch, 46, shown in the form of a receptacle containing a body of mercury in which is immersed one end of an electrode, 49, connected with wire, 47. The other electrode, 50, is movable into and out of contact with said body of mercury by means of a lever, 51, fulcrumed at 52 upon the frame of the machine with one end of which lever the electrode, 50, is pivotally connected.

A wire, 53, connects said electrode, 50, with one end of the coil of solenoid, 19, the other end of said solenoid being connected by wire, 54, with the main supply wire, 48.

A coil-spring, 55, connecting the lever, 51, with the frame of the machine tends to yieldingly support the lever with the electrode, 50, withdrawn from contact with said body of mercury in which position the circuit through solenoid, 19, is opened.

A yielding dog, 95, is pivotally mounted upon the other end of said lever, 51, and is yieldingly held by spring, 56, in position to be engaged by a rod, 57, vertically reciprocatory in a bearing on the frame of the machine.

The lower end of the rod, 57, is operatively connected with an L-shaped offset, 58, which projects rearwardly from a foot-operated lever, 59, having a foot-rest, 60, which lever is fulcrumed at 61 upon the frame of the machine.

Downward pressure upon the foot-rest, 60, will thus raise the end of lever, 51, which carries the dog, 95, causing the other end of the lever to force the electrode, 50, down into contact with the body of mercury in the switch, 46, to close the circuit through solenoid, 19, thus causing the templet to be forced downward upon the bed or an interposed blank.

The supply of electric current to the solenoid, 35, is controlled by means of a pair of switch-contacts, 62 and 63.

The contact, 63, is mounted upon the frame of the machine, and is connected by wire, 64, with the wire, 53, to which electric current is supplied through the electrode, 50, of the switch, 46.

The other contact, 62, is mounted upon the templet actuating-rod, 15, in position to engage the contact, 63, as the templet is lowered upon the bed.

The contact, 62, is connected by wire, 65, with one end of the coil of solenoid, 35, the other end of said coil being connected by wire, 66, with the main supply wire, 48.

The solenoid, 35, can thus be energized 65 only after the solenoid, 19, has been energized and has caused the templet to be forced down upon the bed, and the energizing electric circuits through both solenoids, 19 and 35, will be simultaneously 70 broken by the elevation of the electrode, 50, of switch, 46.

The solenoid, 35, when energized as above described forces the infolders inwardly over the edges of the templet to infold the edges 75 of the blank.

The supply of electric current to the solenoid, 44, is supplied by an electric switch, 67, similar to the switch, 46, and having a fixed electrode, 68, connected by wire, 69, 80 with the main supply wire, 47, and a movable electrode, 70, connected by wire, 71, with one end of the coil of solenoid, 44, the other end of said solenoid being connected by wire, 72, with the wire, 66, and thus 85 with the main supply wire, 48.

The movable electrode, 70, is moved into and out of contact with the body of mercury within switch, 67, by means of a lever, 73, connected with the frame of the machine 90 by a coil-spring, 74, which tends to force the electrode, 70, down into contact with said body of mercury in switch, 67.

The lever, 73, which is pivoted at 75 upon the frame of the machine is at certain times 95 raised and held in raised position against the force of the spring, 74, by means of a cam, 76, on one end of a slide-bar, 77, which reciprocates longitudinally through a slide-way, 78, fixed upon the frame of the machine, said cam being engageable with a pin or roller, 86, projecting laterally from said lever.

A dog, 79, is pivoted at 80 upon the other end of said slide-bar, 77, said dog being provided with a notch, 81, adapted to engage a pin, 82, fixed upon the arm, 32.

A coil-spring, 85, connects the dog, 79, with the frame of the machine, tending to yieldingly force said dog into engagement 110 with said pin, 82, and also to yieldingly force the slide-bar, 77, in a direction to cause its cam, 76, to engage the pin or roller, 86, on the lever, 73.

A lever, 87, is pivoted at 88 upon the 115 frame of the machine in position for one of its ends to engage the dog, 79, its other end being connected by a link, 89, in an arm, 90, in fixed relation to the foot-lever, 59, which foot-lever is yieldingly held raised by a coil-spring, 91, connecting said foot-lever with the frame of the machine.

When the machine is idle, the position of said lever, 87, and the dog, 79, are as shown in Fig. 5, said dog being withdrawn from engagement with the pin, 82, but being located with its notch, 81, opposite said pin in position to engage the same when the dog is

released by movement of the lever, 87, accompanying a downward movement of the foot-rest, 60; and when said pin, 82, is engaged by the notch, 81, the parts are so interlocked that the movement imparted to the arms, 32, accompanying the inward movement of the infolders causes the slide-bar, 77, to be moved in opposition to the force of the spring, 85, to withdraw the 10 cam, 76, from beneath the pin or roller, 86, permitting the spring, 74, to force downward the lever, 73, and movable electrode, 70, to close the circuit through solenoid, 44, and thus cause the bed, 2, to be forced upward to press the folded blank between the bed and the infolders, as above described.

The upward movement of the shaft, 27, which is thus caused in raising the bed, 2, causes the arm, 31, on said shaft to engage a 20 trip-lever, 92, fulcrumed at 93 upon the frame of the machine, causing said lever to engage the dog, 95, and force the same out of engagement with the rod, 57, thus releasing the lever, 51, to the action of spring, 25 55, which immediately causes the electrode, 50, to be withdrawn to open the switch, 46, and thus to deenergize both solenoid, 19, and solenoid, 35.

The operation of the machine is as follows:

A blank having been placed upon the bed the operator presses downward with the foot upon the foot-rest, 60, which operation forces upwardly the rod, 57, and forces the 35 lever, 87, out of engagement with the dog, 79, the notched portion of the dog thereupon immediately engaging the pin, 82.

The upward movement of the rod, 57, by engagement with the dog, 95, actuates the 40 lever, 51, to close switch, 46, thus energizing solenoid, 19, and thereby causing the templet to be forced down upon the blank on the bed as above described.

The downward movement of the templet 45 is accompanied by a downward movement of the rod, 15, which forces the contact, 62, against the contact, 63, thus closing the circuit through solenoid, 35, energizing said solenoid to cause the inward movement of 50 the infolders, as above described, the infolders thus inturning the edges of the blank over the edge portions of the templet.

The notched portion of the dog, 79, having been drawn into engagement with the 55 pin, 82, by the initial downward pressure of the foot-rest, 60, the movement of the arm, 32, which is caused by the movement of shaft, 27, in accomplishing the inward movement of the infolders, operates the 60 slide-bar, 77, to withdraw the cam, 76, from beneath the pin or roller, 86, thus permitting switch, 67, to be closed by the spring-induced downward movement of lever, 73, and electrode, 70, to open the switch, 67.

The solenoid, 44, being thus energized forces the pressing lever, 83, 65 upward to raise the bed, 2, to press the folded blank between the bed and the infolders in the manner above described.

The upward movement of the shaft, 27, which accompanies the upward movement 70 of the bed causes the trip-lever, 92, to disengage the dog, 95, from the rod, 57, whereupon the switch, 46, is automatically opened, as above described thus deenergizing the solenoids, 19 and 35, as soon as the operation of pressing the blank begins.

The pressing of the blank can be continued as long as the foot-rest, 60, is held depressed enabling the operator to press the blank as long as he deems advisable, and 80 this without waste of electrical energy which would occur if the solenoids, 19 and 35, were permitted to remain in circuit during the pressing operation.

The pressure of the bed upwardly against 85 the infolders is resisted by blocks, 96, fastened to the top of the machine overhanging the respective infolders.

It will be understood that the infolders are thus pressed against the blocks, 96, with 90 sufficient force to prevent their withdrawal under the influence of the spring, 97, until the bed pressure is released. The infolders will, in turn, by overlapping the templet prevent the templet from being raised by 95 the spring, 12, until the infolders are withdrawn.

Upon the completion of the pressing operation, the operator by raising his foot releases the foot-lever, 59, permitting the bed 100 to drop until the bed supporting frame, 24, rests upon the posts, 36. The bed pressure being thus released, the infolders are automatically moved outwardly by the spring, 97, permitting the templet to be raised by 105 means of the spring, 12.

Releasing the foot-lever, 59, also causes the immediate operation of the lever, 87, which forces the dog, 79, out of engagement with the pin, 82, thus releasing the slide-bar, 110 77, to the action of the spring, 85, which causes the cam, 76, to engage the pin or roller, 86, thereby raising the lever, 73, and electrode, 70, to open the switch, 67.

The eccentrics, 11, are connected with the 115 respective infolders by means of eccentric-straps, 104, and the eccentrics, 11^a, are similarly connected with the respective infolders, by means of eccentric-straps, 105.

Each of these eccentric-straps has a member, 106, overhanging the respective infolders and provided with an opening, 107, through which a screw-bolt, 108, freely passes, said screw-bolt fitting a similarly threaded opening in the infolder. Said 120 screw-bolt also passes through a clamp-plate, 109, which overhangs the eccentric-strap member, 106, and thereby serves to 125

securely clamp the eccentric-strap to the infolder. This manner of connection affords a ready means for adjustment of the infolders relatively to the respective eccentrics, as by loosening the screw-bolt, 108, the position of the infolder can be adjustably changed with relation to the eccentric-strap and the parts then securely clamped in the adjusted position by tightening said screw-bolt.

10 The slideways, 10^b, and 10^c, for the rod, 10, are preferably formed integral with the respective eccentric straps, 105, as shown.

15 What I claim as new and desire to secure by Letters Patent is—

1. In a machine of the class described and in combination, a frame having a top; an infolder movable inwardly and outwardly over said top; an eccentric-strap connected 20 with said infolder; a rotatory shaft extending vertically through said top projecting above the plane of said eccentric-strap; means located beneath said top for imparting rotative movement to said shaft; an 25 eccentric within said eccentric-strap having a sleeve surrounding said shaft above the eccentric-strap; and means whereby said sleeve can be fixed to said shaft in different positions of rotative adjustment.

30 2. In a machine of the class described and in combination, a frame having a top; a pair of infolders movable inwardly and outwardly over said top; eccentrics for operating said infolders; eccentric-straps connecting the infolders with the respective eccentrics; means for rotatively moving said eccentrics; and a slide-connection between said eccentric-straps in longitudinally slid- 35 able relation to one of said straps.

40 3. In a machine of the class described and in combination, a bed; a templet; a pair of corner-infolders and an intermediate infolder coöperative with the same side of the templet; eccentrics for moving said corner-infolders inwardly and outwardly through arcuate paths; and means for moving said intermediate infolder inwardly and outwardly independently of said corner-infolders, said means including cams in fixed 45 relation to the respective eccentrics.

4. In a machine of the class described and in combination, a bed; a templet; a pair of corner-infolders and an intermediate infolder coöperative with the same side of the templet; a pair of rotatively mounted 55 shafts; eccentrics carried by the respective shafts for moving the corner-infolders inwardly and outwardly in arcuate paths; and means for moving said intermediate infolder inwardly and outwardly independently of said corner-infolders, said means including cams carried by the respective shafts, said cams and said eccentrics being adjustably mounted with relation to the respective 60 shafts and to each other.

5. In a machine of the class described and in combination, a bed; a templet; a pair of corner-infolders and an intermediate infolder coöperative with the same side of the templet; a pair of rotatively mounted 70 shafts; eccentrics carried by the respective shafts for moving the corner-infolders inwardly and outwardly in arcuate paths; a pair of levers connected with said intermediate infolder for moving the same inwardly 75 independently of the corner-infolders; and cams on the respective shafts engageable with said levers respectively.

6. In a machine of the class described and in combination, a bed; a templet; a pair of 80 corner-infolders and an intermediate infolder coöperative with the same side of the templet; means for operating said corner-infolders; means for operating said intermediate infolder independently of the corner-infolders; and an automatically adjustable guide for said intermediate infolder.

7. In a machine of the class described and in combination, a bed; a templet; a pair of corner-infolders and an intermediate infolder coöperative with the same side of the templet; eccentric mechanism whereby the corner-infolders are moved inwardly and outwardly in arcuate paths; means whereby said intermediate infolder is moved inwardly and outwardly independently of said corner-infolders, said intermediate infolder being provided with a slideway extending in the direction of its inward and outward movement; and a slide-bar engageable with 95 said slideway and pivotally mounted at its outer end upon a fixed part of the machine.

8. In a machine of the class described and in combination, a frame having a top; a templet; a pair of corner-infolders and an intermediate infolder coöperative with the same side of the templet; an eccentric-strap connected with each of said corner-infolders; a pair of rotatory shafts projecting above the plane of said eccentric-straps; means located beneath the top for imparting rotative movement to the respective shafts; eccentrics within the respective eccentric-straps, said eccentrics having sleeves surrounding the respective shafts above said eccentric-straps; means whereby said eccentric-sleeves are fixed to the respective shafts with capability of rotative adjustment thereupon; cams adjustably fixed upon the respective shafts above said eccentric-sleeves; and means whereby said cams are caused to move said intermediate infolder inwardly independently of the corner-infolders.

9. In a machine of the class described and in combination, a corner-infolder; eccentric 125 mechanism for actuating said corner-infolder; an operating member; a rotatory member; link-connections between said rotatory member, and said eccentric mechanism and said operating member respec- 130

tively; and means whereby one of said link-connections can be connected with said rotatory member at different distances from its axis of movement whereby the length of 5 movement of the eccentric mechanism can be varied.

10. In a machine of the class described and in combination, a bed; a templet; means for moving the templet toward and from the 10 bed; an infolder movable inwardly and outwardly over the bed; means for moving said infolder inwardly and outwardly; means including a solenoid for causing a relative pressing movement between the bed and the 15 infolder; a switch controlling the circuit whereby said solenoid is energized; and means whereby said switch is automatically closed by the inward movement of the infolder.

20 11. In a machine of the class described and in combination, folding and pressing elements comprising a vertically movable bed, a templet movable toward and from the bed, and an infolder movable inwardly 25 and outwardly over the bed, one of said elements comprising the bed and infolder being capable of a pressing movement toward the other; means, including a solenoid, for actuating each of said elements in the operation of folding and pressing a blank; a prime actuating member under the control 30 of the operator of the machine; and means whereby operation of said prime actuating member automatically causes the means for 35 actuating said elements to successively move the templet toward the bed, move the infolder inward over the edge of the templet, and cause a relative pressing movement between the bed and the infolder.

40 12. In a machine of the class described and in combination, a bed; a templet movable toward and from the bed; an infolder movable inwardly and outwardly over the bed; a prime actuating member under the 45 control of the operator of the machine; means whereby operation of said prime actuating member causes the templet to be moved toward the bed; means whereby the movement of the templet toward the bed 50 causes the infolder to be moved inwardly over the edge of the templet; and means whereby the inward movement of the infolder automatically causes a relative pressing movement between the bed and the infolder.

55 13. In a machine of the class described and in combination, a bed; a templet movable toward and from the bed; an infolder movable inwardly and outwardly over the 60 bed; a prime actuating member under the control of the operator of the machine; means whereby operation of said prime actuating member causes the templet to be moved toward the bed; means whereby the 65 movement of the templet toward the bed

causes the infolder to be moved inwardly over the edge of the templet; means, including a solenoid, for causing a relative pressing movement between the bed and the infolder; a switch controlling the circuit 70 whereby said solenoid is energized; and means whereby said switch is automatically closed by the inward movement of the infolder.

14. In a machine of the class described and in combination, a bed; a templet movable toward and from the bed; an infolder movable inwardly and outwardly over the bed; means, including a solenoid, for moving the templet toward the bed; separate 80 means, including a solenoid, for moving the infolder inwardly; separate means, including a solenoid, for causing a relative pressing movement between the bed and the infolder; a switch controlling the circuit 85 whereby said first-mentioned solenoid is energized; means under the control of the operator of the machine for closing said switch; a switch controlling the circuit whereby said second-mentioned solenoid is 90 energized; means whereby said last-mentioned switch is automatically closed by the movement of the templet toward the bed; a switch controlling the circuit whereby said third-mentioned solenoid is energized; and means whereby said last-mentioned switch is automatically closed by the 95 inward movement of the infolder.

15. In a machine of the class described and in combination, a bed; a templet movable toward and from the bed; an infolder movable inwardly and outwardly over the bed; means, including a solenoid, for moving the templet toward the bed; separate 100 means, including a solenoid, for moving the infolder inwardly; separate means, including a solenoid, for causing a relative pressing movement between the bed and the infolder; a switch controlling the circuit whereby said first-mentioned solenoid is 105 energized; means under the control of the operator of the machine for closing said switch; a switch controlling the circuit whereby said second-mentioned solenoid is energized; means whereby said last-mentioned switch 110 is automatically closed by the movement of the templet toward the bed; a switch controlling the circuit whereby said third-mentioned solenoid is energized; means whereby said last-mentioned switch 115 is automatically closed by the inward movement of the infolder; and means whereby said first-mentioned and second-mentioned solenoids are automatically deenergized by said pressing movement.

16. In a machine of the class described and in combination, a bed; a templet movable toward and from the bed; an infolder movable inwardly and outwardly over the bed; means for moving the templet toward 120

and from the bed; means, including a solenoid, for moving the infolder inwardly; a switch controlling the circuit whereby said solenoid is energized; means for closing said switch; separate means, including a solenoid, for causing a relative pressing movement between the bed and the infolder; a switch controlling the circuit whereby said last-mentioned solenoid is energized; means whereby said last-mentioned switch is automatically closed by the inward movement of the infolder; and means whereby said first-mentioned switch is automatically opened by said pressing movement.

17. In a machine of the class described and in combination, a bed; a templet movable toward and from the bed; an infolder movable inwardly and outwardly over the bed; means, including a solenoid, for moving the templet toward the bed; separate means, including a solenoid, for moving the infolder inwardly; separate means, including a solenoid, for causing a relative pressing movement between the bed and the infolder; a switch controlling the circuits by which said first-mentioned and said second-mentioned solenoids are energized; a normally open switch in the circuit between said first-mentioned switch and said second-mentioned solenoid; means under the control of the operator of the machine for closing said first-mentioned switch; means whereby said second-mentioned switch is automatically closed by the movement of the templet toward the bed; a switch controlling the circuit whereby said third-mentioned solenoid is energized; means whereby said last-mentioned switch is automatically closed by the inward movement of the infolder; and means whereby said first-mentioned switch is automatically opened by said pressing movement.

18. In a machine of the class described and in combination, a bed; a templet movable toward and from the bed; an infolder movable inwardly and outwardly over the bed; means for moving the templet toward the bed; means including a solenoid, for moving the infolder inwardly; a switch controlling the circuit whereby said solenoid is energized; means for closing said switch; means for causing a relative pressing movement between said infolder and said bed; and means whereby said switch is automatically opened by said pressing movement.

19. In a machine of the class described and in combination, a bed; a templet movable toward and from the bed; an infolder movable inwardly and outwardly over the bed; means, including a solenoid, for moving the templet toward the bed; means, including a solenoid, for moving the infolder inwardly; a switch controlling the circuit

whereby said first-mentioned solenoid is energized; means under the control of the operator of the machine for closing said switch; a switch controlling the circuit whereby said second-mentioned solenoid is energized; means whereby said last-mentioned switch is automatically closed by the movement of the templet toward the bed; means for causing a relative pressing movement between the bed and the infolder; and means whereby both of said solenoids are deenergized by said pressing movement.

20. In a machine of the class described and in combination, a bed; a templet movable toward and from the bed; an infolder movable inwardly and outwardly over the bed; means for moving the templet toward the bed; means for moving the infolder inwardly; means, including a solenoid, for causing a relative pressing movement between the bed and the infolder; a switch controlling the circuit whereby said solenoid is energized; means, including an actuating member under the control of the operator of the machine, whereby said switch is closed; and means whereby said switch is automatically opened by the release of said actuating member.

21. In a machine of the class described and in combination, a bed; a templet movable toward and from the bed; an infolder movable inwardly and outwardly over the bed; means for moving the templet toward the bed; means, including a solenoid, for moving the infolder inwardly; a switch controlling the circuit whereby said solenoid is energized; means, including an actuating member under the control of the operator of the machine, for closing said switch; means, including a solenoid, for causing a relative pressing movement between the bed and the infolder; a switch controlling the circuit whereby said last-mentioned solenoid is energized; means whereby said last-mentioned switch is automatically closed by the inward movement of the infolder; means whereby said first-mentioned switch is automatically opened by said pressing movement; and means whereby said second-mentioned switch is automatically opened by the release of said actuating member.

22. In a machine of the class described and in combination, a bed; a templet movable toward and from the bed; an infolder movable inwardly and outwardly over the bed; means, including a solenoid, for moving the templet toward the bed; separate means, including a solenoid, for moving the infolder inwardly; separate means, including a solenoid, for causing a relative pressing movement between the bed and the infolder; a switch controlling the circuit whereby said first-mentioned solenoid is energized; means, including an actuating member under the control of the operator

of the machine, for closing said switch; a switch controlling the circuit whereby said second - mentioned solenoid is energized; means whereby said last-mentioned switch is automatically closed by the movement of the templet toward the bed; a switch controlling the circuit whereby said third-mentioned solenoid is energized; means whereby said last-mentioned switch is automatically closed by the inward movement of the in-

folder; means whereby said first-mentioned and said second-mentioned solenoids are automatically deenergized by said pressing movement; and means whereby said last-mentioned switch is automatically opened by the release of said actuating member.

In testimony whereof I have hereunto set my hand this 14th day of September, 1917.

WALTER J. BEATTIE.
